N. S. Vedder Assignor to A. T. Gunham & Co.
Stove designer Patented 29th July 1851.

Res. 404

N S Vedder of Troy N.Y.
Letters Patent dated July 29 1851
(as signed to A. J. Dunham & Co.)

No 404

The Schedule annexed to my these letters patent and making part of the same
To all whom these presents shall come. Be it known that I, Nicholas

Des. 404

W

N. Wedder of Troy in the County of Rensselaer and State of New York
have invented or produced a new design of cast iron stove which I call
the "Fashion of Troy" and I do hereby declare that the following
is a full and exact description of a part of the same referred
being had to the annexed drawing making a part of this spe-
cification which is a view of one side plate and door

The ornamental design of my stove consists of stars a.a
on the doors and rays b.b issuing therefrom those running
to the corners c.c are divided forming small square cones and
the body of the stove is ornamented with diamonds d.d as
represented

What I claim and desire to secure by letters patent
is the design and configuration of ornaments as applied to
stoves substantially the same as described
